AUTOMATIC VALVE-OPERATING MECHANISM.

1,192,774.

Specification of Letters Patent.

Patented July 25, 1916.

Application filed June 25, 1915. Serial No. 36,294.

To all whom it may concern:

Be it known that we, CHARLES GEORGE EIDSON and THOMAS DAVIS, citizens of the United States, and residents of the city of Baltimore, in the State of Maryland, have invented certain new and useful Improvements in Automatic Valve-Operating Mechanisms, of which the following is a specification.

10. Our invention relates to improvements in automatic valve operating mechanisms, and it consists in the combinations, constructions, and arrangements herein described and claimed.

15. An object of our invention is to provide a device by means of which valves may be operated which control the flow of air into and out of a pressure tank, the device being so arranged as to cause the operation of the 20 valves when the pressure reaches a predetermined minimum and afterward to cause the reverse movement of the valves when the pressure reaches a predetermined maximum.

25. A further object of our invention is to provide a device of the type described in which the movement of the valve is accomplished suddenly by novel mechanism which positively insures the operation of the valve at the point determined.

30. A further object of our invention is to provide a device of the type described in which a slow and extended movement of certain of the parts results in a quick short movement of the valve, means being interposed between these parts for compensating for lost motion.

35. Other advantages and objects will appear in the following specification and the novel features of the invention will be particularly pointed out in the appended claims.

40. Our invention is illustrated in the accompanying drawings forming part of this application in which—

45. Figure 1 is a sectional view through the valve operating mechanism. Fig. 2 is a face view of the valve operating mechanism, certain parts being shown in section. Fig. 3 is a detail view of one of the slidable locking members. Fig. 4 is a diagrammatical 50 view showing the manner in which the valve operating mechanism is used. Fig. 5 is a detail view of one of the slidable members of the valve. Fig. 6 is a detail view of another slidable member. Fig. 7 is a trans-

verse section through the device substantially 55 on the line 7—7 of Fig. 2. Fig. 8 is a longitudinal sectional view of the slidable member shown in Fig. 5, and Fig. 9 is an end view of the slidable member shown in Figs. 5 and 8.

60. Referring now to Fig. 1, it will be seen that we have provided a cylindrical housing 1 which has a closed end 2 provided with an opening 3 arranged to receive a cylindrical member 4. The latter has a threaded portion 4* into which is screwed a threaded portion 5* of a stem 5 bearing a head 6. A spiral spring 7 bears on the head 6 at one end and at the other end on a plate 8 which may be adjusted by set screws 9 passing 70 through the end 2.

75. The head 6 projects into a chamber 10 in which is disposed a diaphragm 11, the diaphragm 11 being arranged to bear on the head 6, as shown in the drawings. The chamber 10 communicates, by means of the passage 12, with the interior of a valve casing 13. This valve casing is provided with a valve 14 arranged to engage a valve seat 15. A spring 16 bears at one end on the valve 14 80 and at the other end on a screw plug 17. The valve 14 is connected by means of a bar 18 with a slidable member 19 one end of which is shaped to form a valve 20 which is arranged to engage a valve seat 21. It will 85 be observed that the valve 14 is at one end of a passage 22 and the valve 20 at the other end, the bar 18 passing through this passage. This bar 18 is of such a length that when the valve 14 is closed, the valve 20 is held 90 open by the bar 18 and vice versa. The slid- 95 able member 19 extends through a guide portion 23 and terminates on the exterior thereof. Air ports 24 and 25 communicate with the interior of the valve casing and 95 with the passage 22 respectively.

Secured to the cylindrical member 1 is a T-shaped bracket 26 which is provided with a longitudinal slot 27 and a transverse slot 28 intersecting the longitudinal slot 27. 100 Slidably disposed in the longitudinal slot 27 is a bar 29, this bar being hollow except for a partition 29* disposed toward one end, see Fig. 8. A spring 30 is disposed within the hollow bar and bears at one end on the partition 29* and at the other end on a collar 31 carried by a plunger 32. On the opposite side of the partition 29* is a spring 33 which

bears on the partition at one end and at the other end on a collar 34 carried by a plunger 35. Pins 36 and 37 limit the movements of the collars 31 and 34 respectively. The bar 29 is provided on one side with a slot 38 and on the opposite side with a slot 39 which, as will be seen from Figs. 5 and 8, is out of registration with the slot 38. A plate 40 is also disposed in the slot or groove 27. 10 The plate 40 bears a slot 41 which has an inclined or beveled edge 41^x while the slot 42 on the opposite side of the plate 40 has an inclined or beveled edge 42^x. The plate 40 is provided with an opening 43 near one 15 end.

The bracket 26 is provided with an extension 26^a while the cylindrical member 5 is provided with an extension 5^a. A lever 44 is fulcrumed at 45 on the extension 26^a and is 20 pivoted to the extension 5^a. The opposite end of this lever is provided with a finger 44^a arranged to extend through the opening 43 in the slidable plate 40. A U-shaped spring 47 straddles the extension 26^a, passes 25 around the fulcrum pin 45, and the arms bear against pins 48 carried by the slidable bar 29. The tension of the spring 47 holds the bar 29 up against the lever 44.

Slidably disposed in the cross slot 28 on 30 each side of the slidable bar 29 and plate 40, are locking members 49 and 50 respectively. As will be seen from Fig. 2, the locking member 50 is hollowed out to receive a spring 50^x, while the inner corner of the 35 member 50 is beveled as shown at 50^y. Similarly the member 49 is provided with a beveled portion 49^y and with a spring 49^x. A T-shaped cap 51 is provided with laterally extending portions 51^a against which the 40 springs 49^x and 50^x bear, thus forcing the members 49 and 50 inwardly toward the slidable members 29 and 40.

From the foregoing description of the various parts of the device, the operation 45 thereof may be readily understood.

In Fig. 4 we have shown diagrammatically one of the uses to which this device may be put, but it will be understood that this diagram is merely for illustration only and 50 that the valve operating mechanism could be used in other relations, for example, to operate an electric switch or a throttle valve of an engine. The primary use of the valve mechanism is in connection with starting systems for internal combustion engines. In 55 Fig. 4, T represents a tank for storing air, E the engine of an automobile or similar vehicle, A—M an air compressor motor, C a clutch, D a diaphragm which operates the 60 clutch. Let us assume that the parts are in the position shown in Fig. 4. In this figure, the engine E is driving the air compressor motor as a compressor which is pumping air through the pipe W into the tank T. The 65 diaphragm casing is connected by a pipe d

with the port 25, see Fig. 1, while a pipe o connects the reservoir T with the interior of the valve casing which in Fig. 4 we have denoted in general by O. The opening into the valve casing is through the port 24, see 70 Fig. 1. It will be seen that the diaphragm D which is collapsed, is in communication with the outer atmosphere through the pipe d, port 25, passage 22, and a small passage 22^p. As pressure increases in the tank T it 75 flows into the space 10 and presses on the diaphragm 11, see Fig. 1, thus gradually forcing the plunger head 6 to the right against the tension of the spring 7, thus freeing the lever 44 and its fulcrum 45. The 80 finger 44^a engages the plunger 32, see Figs. 1 and 8, thus tending to compress the spring 30 within the slidable member 29. The latter cannot move, however, because it is locked in position by means of the slidable 85 block 50.

As the pressure increases, the diaphragm 11 tends to press the head 6 farther inwardly, thus moving the plate 40 through which the finger 44^a extends, along the slot 90 27. Now when the beveled portion 42^x of the plate 40 reaches the beveled portion 50^y of the block 50, it will force the latter out of the slot 39, see Fig. 5. As soon as the block 50 clears the edge of the slot, then the bar 29 will move suddenly forward under the influence of the spring 30, and main spring 7 thereby causing the plunger 35 to engage the slidable member 19 which bears the valve 20 at its opposite end, thus causing the closing of the valve 20 and the opening of the valve 14, see Fig. 1. The pressure now coming from the reservoir will pass by means of the passage 22, into the pipe d through the port 25 and will tend to push the diaphragm D outwardly into the position shown in dotted lines in Fig. 4, thus moving the clutch C so as to disengage the engine E from the compressor, and thus stop the latter. When the bar 29 moves forwardly, the locking block 49 enters the slot 38 thus locking the member 29 into position. Now when the pressure in the tank decreases as the air is being used up for any purpose whatever, the spring 7 gradually causes the 110 lever 44 to move in the opposite direction. The bar 29 is under tension of the spring 47, but it cannot follow the lever in its movement because it is locked by the lock 49. The plate 40, however, is retracting and when the beveled portion 41^x of the plate 40 reaches the beveled portion 49^y of the block 49 it will force the block outwardly and thus out of the slot 38. As soon as the block 49 clears the slot 38 the spring 47 will suddenly throw the bar 29 to the right in Fig. 1, and the spring 16 which bears on the valve 14 as well as the other pressure will cause the closing of the valve 14 and the opening of the valve 20, thus shutting off the air-pressure from 120 125 130

the diaphragm and permitting the escape of the air on one side of the diaphragm through the pipe *d*, port 25, and through the exhaust opening 22°. The spring *S*, Fig. 4, 5 will now bring the clutch *C* into position so as to cause the driving of the compressor by the engine again.

It will thus be seen that we have provided a device which automatically operates the 10 valve in accordance with the pressure. As a matter of fact, the movements of the valves 14 and 2 are very slight compared with the movement of the plunger head 6 or with the lever 44. The provision of the 15 springs 30 and 33 in the slidable bar 29, takes up lost motion and tends to permit the use of a plunger having a relatively long stroke with respect to the movement of the valves.

20 The tension of the spring 7 may be regulated by means of the set screws 9 which bear on the plate 8. By this means the maximum point at which the valves shift may be regulated, so that the valves may shift at a 25 higher or lower maximum pressure. The range between the maximum and the minimum pressure is regulated by the tension of the spring 30 in the bar 29, and also by the size of the wire and the pitch of the 30 spring 7.

We claim:—

1. An automatic valve operating mechanism comprising, a plunger, a movable member having operative engagement with the 35 valve, means associated with said plunger for placing the said movable member under spring tension, means for locking said movable member during the initial movement of the plunger, and means actuated by a further movement of the plunger to retract the locking means.

2. An automatic valve operating mechanism comprising, a plunger, a slidable member adapted to be brought into operative 45 engagement with the valve, means for placing the slidable member under spring tension during the initial movement of the plunger, means for preventing the movement of the slidable member during said 50 initial movement, means for retracting the locking means to permit movement of said slidable member, means for locking said slidable member at the end of its forward movement, and means for retracting the 55 slidable member on the release of the locking means.

3. The combination with a valve, of automatic means for operating the same, said means comprising a plunger, a slidable 60 member arranged to engage the valve stem, connections between said plunger and said valve for operating the latter, means associated with the slidable member for preventing movement of said slidable member until 65 the plunger has moved through a portion of

its stroke, and means also operating to prevent a reverse movement of the slidable member until the plunger has virtually completed its reverse stroke.

4. An automatic valve operating mechanism comprising a pressure chamber, a diaphragm disposed therein, a plunger arranged to be engaged by said diaphragm, a spring on the opposite side of said plunger from the diaphragm, a slidable member 75 arranged to engage the valve for operating the same, a lever actuated by said plunger and arranged to engage said slidable member, means for locking said slidable member during the initial movement of the plunger in one direction, means for locking the slidable member during the initial movement of the plunger in the opposite direction, and common means for releasing both of said locking means at a predetermined 85 point in the movement of said plunger.

5. An automatic valve operating mechanism comprising a pressure chamber, a diaphragm disposed therein, a plunger arranged to be engaged by said diaphragm, a spring on the opposite side of said plunger from the diaphragm, a slidable member arranged to engage the valve for operating the same, a lever actuated by said plunger and arranged to engage said slidable member, means for locking said slidable member during the initial movement of the plunger in one direction, means for locking the slidable member during the initial movement of the plunger in the opposite direction, and common means for releasing both of said locking means at a predetermined point in the movement of said plunger, said last-named means comprising an independently movable cam plate arranged to engage said locking means successively, said cam plate being operatively connected with the lever which operates said slidable member. 100 105

6. The combination with a valve casing, a pressure chamber communicating therewith, a valve disposed in said valve casing, a slidable member arranged to engage the valve for opening the latter, a diaphragm in said pressure chamber, a spring pressed plunger operated by said diaphragm, a lever pivotally connected with one end of said plunger and arranged to bear on said slidable member at the other end, a pair of locking members associated with said slidable member, one of said locking members 110 being arranged to lock the slidable member against the initial movement of the plunger in one direction and the other locking member being arranged to lock the slidable member against the initial movement of the plunger in the opposite direction, and a slidable cam plate arranged to release said locking means in succession. 115 120 125

7. An automatic valve operating mechanism comprising, a slidable bar having lock, 130

- ing recesses on opposite sides, locking blocks arranged to enter said recesses, each of said blocks being provided with a beveled surface, and a cam plate slideable longitudinally 5 on said bar and provided with a cam surface arranged to engage the beveled surfaces of said locking blocks for forcing the latter out of locking engagement with the slideable bar.
- 10 8. An automatic valve operating mechanism comprising, a slideable bar having locking recesses on opposite sides, locking blocks arranged to enter said recesses, each of said blocks being provided with a beveled surface, and a reciprocatory cam plate having cam surfaces arranged to engage one of said blocks during its movement in one direction for forcing said block out of locking engagement with said slideable bar and for engaging 15 the other block during the reverse movement of the cam plate.
9. An automatic valve operating mechanism comprising, a slideable bar adapted to be brought into operative relation with the valve, said bar having locking recesses in its 25 opposite sides, spring pressed plungers in the interior of the bar, the ends of the plungers being arranged to project beyond the end of the bar, a cam plate slideable longitudinally on said bar, a locking block on 30 each side of said bar and arranged to enter one of the locking recesses, a cam plate having cam surfaces arranged to engage said locking blocks so as to force the latter out of locking engagement, and common means for 35 moving said cam plate and said slideable bar.
